UNITED STATES PATENT OFFICE

103,161

DESIGN FOR A COMBINED SERVICE WAGON
AND PERAMBULATOROtto F. Opperman and Gilbert Betancourt, Santa
Monica, Calif.

Application April 25, 1936, Serial No. 62,311

Term of patent 3½ years

To all whom it may concern:

Be it known that we, Otto F. Opperman and Gilbert Betancourt, citizens of the United States, residing at Santa Monica, county of Los Angeles, State of California, have invented a new, original, and ornamental Design for a Combined Service Wagon and Perambulator, of which the following is a specification, reference being had to the accompanying drawing, forming part thereof.

Figure 1 is a perspective view of a combined service wagon and perambulator showing our new design.

Figure 2 is a view in end elevation of a combined service wagon and perambulator showing our new design with the covers raised as indicated in dotted lines.

Figure 3 is a view in side elevation of a combined service wagon and perambulator showing our new design.

Figure 4 is a perspective view similar to Figure 1, but on a slightly reduced scale and with the covers removed.

The device of our design is a service wagon in closed position and a perambulator when in the open position with top removed.

We claim:

The ornamental design for a combined service wagon and perambulator, as shown and described.

OTTO F. OPPERMAN.
GILBERT BETANCOURT.
